RADIORECEIVER

Original Filed Feb. 9, 1927 2 Sheets-Sheet 2

UNITED STATES PATENT OFFICE

BOWDEN WASHINGTON, OF NEW YORK, N. Y., ASSIGNOR TO REMOTROLE CORPORATION,
A CORPORATION OF NEW YORK

RADIO RECEIVER

Original application filed February 9, 1927, Serial No. 166,992. Divided and this application filed September 6, 1927. Serial No. 217,707.

One object of my invention is to produce a remote controlled radio receiver in which the wavelength to which it best responds and the volume of the output may be controlled from a distant point without the use of connecting wires, cables or chains.

The main object is to provide apparatus for use with existing receivers or amplifiers to attain the above mentioned results. The modern broadcast receiver has sufficient undistorted output to be clearly heard anywhere on a single floor of the average dwelling house or anywhere in the average apartment. A receiver of this type is too large and heavy to be conveniently movable from room to room. Yet, it is most annoying for the listener to have to remain by the receiver in order to effect a change of program, when desired, or to be continually getting up and going to the receiver to change the program or the volume.

One object is to provide a method of reception and control which will make it possible for the operator to enjoy such program as he desires with a minimum effort.

By means of my invention, which will not add prohibitively to the cost of the receiver, both these adjustments may be effected from a distance. The control box may be made small and light enough to be readily portable. Its power may be supplied from the alternating current house mains or other source and it may be provided with a cord and plug so that it may be attached to any existing lamp socket, base plug or other outlet.

This application is a division from my application No. 166,992 filed Feb. 9, 1927, in which the invention is broadly claimed.

Referring to the drawings, Fig. 1 is a schematic wiring diagram of the principal parts of a receiver embodying one form of my invention with a schematic wiring diagram of its control station.

Fig. 2 is a partly schematic and partly dia-grammatic drawing of a form of my invention which may be readily associated or used with the usual tuned radio frequency receiver or other sufficiently sensitive set.

In Fig. 1 the antenna 5 is connected to the ground 6 through the primary 7 of the band

amplifying transformer 7'. The secondary 8 of this transformer is connected to the grid 9 and the filament 10 of the tube 11. The plate 12 is connected through the primary 13 to the anode voltage supply line 14. The primary 13 and the secondary 15 form a second band amplifying transformer 13' constituting the input circuit of the tube 16.

The output circuit of the tube 16 is coupled by means of the band amplifying transformer 17 to the detector tube 18 which may be provided with the grid leak 19 and the grid condenser 20. The output of the tube 18 includes an intermediate frequency resonant circuit frequently called a "filter circuit" consisting of a condenser 21 and the inductance 22. The inductance 22 forms the primary of the intermediate frequency transformer 23 having a secondary 24 included in the grid circuit of the intermediate frequency amplifying tube 25. Two additional intermediate frequency transformers 26 and 28 may be provided with their respective tubes 27 and 29. The output of the tube 29 is coupled by intermediate frequency transformer 30 to the in-put circuit of the detector tube 31. This circuit consists of the secondary inductance 32, the grid leak 33 and the grid condenser 34. Terminals 35 and 36 are provided so that the output of the detector 31 may be introduced into any suitable indicating device such as an audio frequency amplifier or head phones (not shown).

The control station 40 may be provided with power in any suitable manner, for instance at its input with a cord and plug 41 for providing alternating current power to the primary 42 of the transformer 43, the amount of power being regulated by the rheostat 44 which serves as a gain control for the receiver. One secondary 45 of this transformer may have its terminals connected to the plates 46 and 47 of the full wave rectifier 48. The filament 49 of this rectifier may be heated from the winding 50 and the filament 51 of the oscillator tube 52 may be heated from winding 50'. The central point of the secondary 50 may be led through the smoothing inductance 54 and the feed back 100

coil 55 to the anode 56 of the oscillator tube 52.

The filtering condensers 57 and 58 may be provided. The grid circuit of the oscillator 5 may consist of the inductance 59, the radiating loop 60 and the variable condenser 61. The grid return of the oscillator may be brought to the central point of resistance 62 which is also connected to a central tap 53 10 of the winding 45.

The tubes 11 and 16 with their associated circuits form a band amplifier which will amplify with substantial uniformity over a desired band of frequencies, such as, the present broadcast band (550 to 1500 kilocycles). A predetermined frequency such as 50 kilocycles may be chosen as a resonant frequency of the filter transformer 23 and as the peak frequency of the following intermediate frequency 15 amplifier system. The band amplifier is provided to make up for the gain lost by not using a resonant input circuit.

In operation, the remote control station 40 is set in operation and the condenser 61 20 is adjusted until the energy radiated from the loop 60 into the input of the receiver differs in frequency from the wave that it is desired to receive by the predetermined frequency chosen for the resonant frequency of 25 the super-audible intermediate frequency amplifier system, thus producing a beat frequency in the output of the tube 18 which is resonant to the intermediate frequency amplifier.

30 The strength of the output of the receiver may be varied by varying the strength of the oscillations radiated from the loop 60 by various means such as the rheostat 44. The loop 60 may preferably be in a horizontal 35 plane, thus polarizing its radiation in a manner least liable to affect other neighboring receivers.

Fig. 2 shows a method of applying my invention to ordinary tuned radio frequency 40 types of receivers. In this case a differential frequency converter unit 80 is provided which is inserted between the antenna system 5 and the input of a receiver 82. In case the input of the receiver 82 includes a 45 series condenser this condenser should be shorted or a radio frequency choke placed across the input terminals to allow for the direct current anode flow. The remote control box oscillator 40 such as heretofore described and shown in Fig. 1 is provided. The converter 80 as illustrated has a two-stage band amplifier and detector similar to that associated with tubes 11, 16 and 18 in Fig. 1.

50 In operation the tuning controls 84, 85 and 86 of the receiver 82 are adjusted in any suitable manner until their associated circuits are resonant to the same frequency, which frequency may preferably be the lowest at which 55 the receiver will operate. For purposes of

explanation, let us assume that this frequency be 500 kilocycles and that the frequency band which it is desired to receive be from 1500 to 550 kilocycles. Then, if the oscillator 40 has a range of 2000 to 1050 kilocycles, 500 kilocycle beats can be produced at will in which case the usual radio frequency part of the receiver 82 will function as an intermediate frequency amplifier. The detector of this set 82 will now function as a second detector 70 for its audio frequency amplifier and excite the loud speaking telephone 87 or other device. 75

Owing to the fact that there is no resonant selectivity at the incoming signal frequency 80 it may be found advisable to employ more than a single stage filter in the intermediate frequency circuits.

It is also advisable to choose such a resonant peak frequency for the intermediate frequency filter amplifier that beats between any two transmitting stations will not be in resonance with this amplifier. For instance, with the present interval between broadcast stations of 10 kilocycles a frequency of 40 or 90 50 kilocycles can be produced by stations 3 or 4 intervals apart but if 45 or 55 kilocycles is chosen this will not occur. To ensure that no difficulties of this sort occur a several section band-pass filter may be incorporated in 95 the filter amplifier which may have its cut-offs at for example 51 and 59 kilocycles.

To attain best tone quality I prefer to adjust the portable oscillator 40 to a frequency which will place the carrier current in the 100 band-pass filter close to one of its cut-offs or limits thus allowing the full frequency range of the filter for one side band. By this method of tuning it is also possible to separate two stations which might differ in 105 frequency equally but above and below the output frequency of the oscillating detector if the intermediate carrier current frequency were midway between the limits of the band-pass filter employed.

110 The differential frequency converter 80 may be sold as a unit for attachment to any standard type of receiver. The control unit 40 may also be sold separately, in fact a number of control units might be installed in 115 various parts of the house for exciting the same receiver.

I do not wish to limit myself to the detection methods, type of oscillating circuits, number of stages, type of oscillator, power 120 supply or type of gain control except in so far as may be set forth in the appended claims and required by the prior art.

I claim:

1. A radio receiving apparatus comprising 125 an antenna system, a band-pass amplifier having an input circuit designed to pass a predetermined band of frequencies and associated with the antenna system, an intermediate frequency amplifier, a detector con- 130

5 nected between the band-pass amplifier and said intermediate frequency amplifier, a filter transformer connected to select the frequency of the signals transmitted to the intermediate frequency amplifier, means for detecting the signal from the intermediate frequency amplifier, and audio frequency amplifying means connected to the output of the detecting means and a remote control unit having 10 an oscillator generating frequencies differing from the incoming signal frequencies by an amount numerically equal to that of the intermediate frequency amplifier and having a radiating loop loosely coupled to the input of the band-pass amplifier.

15 2. The combination of non-selective means for collecting broadcast signals of various frequencies, independently portable means for producing any desired frequency of control oscillations within a predetermined band of frequencies, means for varying the amplitude and frequency of the control oscillations, means for radiating the control oscillations, non-selective means for receiving and 20 amplifying the collected signals and the control oscillation, means for mixing and detecting the amplified broadcast signal energy and the radiated control energy with the production of a certain super-audible frequency outside of the band-pass range, means 25 for amplifying the resultant superaudible frequency, and means for redetecting said latter amplified energy, the frequency of control oscillations differing from the incoming broadcast signal frequencies by an amount 30 numerically equal to the response frequency of the super-audible frequency amplifier.

35 3. A radio receiver having in combination a control oscillator, means for radiation of output of said control oscillator, means for the simultaneous collection of signals throughout a broad band of frequencies and of control oscillations, means for amplification of both signals and control oscillations 40 with substantial uniformity regardless of frequency, means for detecting said signals and said control oscillations so as to produce a series of signals of frequencies differing from the frequencies of the control oscillations 45 and the signals, means for selecting a predetermined differing frequency, means for adjusting the control oscillations so as to transfer the modulations of the desired signal to said predetermined differing frequency, means for the amplification and demodulation of said predetermined differing frequency and means for the amplification of the demodulations, said control oscillator being 50 separate and located at a short distance from the remainder of the receiver.

55 4. Means for controlling a broadcast receiver from a distance comprising, a differential frequency converter adapted to be directly connected to the receiver and a sepa-

rate remote control oscillator unit, said converter consisting of an untuned amplifier for receiving all available signals within the frequency range of said broadcast receiver, and also receiving and amplifying the oscillations from the control unit, means for detecting said oscillations and said signals to produce signals of frequencies equal to the difference between the frequencies of the control oscillations and the signals, said detecting means having its output adapted for connection to the broadcast receiver, said control oscillator unit having means for varying the frequency of the produced oscillation in order to adjust the desired signal to the frequency to which the broadcast receiver is tuned.

70 5. The method of selective radio reception controlled from a distance such as within the limits of an ordinary apartment, which comprises, collecting all available signals in the range of the receiver within a predetermined band of frequencies covering a plurality of signal channels, producing oscillations of a control frequency and radiating the same a short distance, collecting said oscillations, amplifying said oscillations and said signals, detecting said oscillations and said signals so as to produce signals of frequencies equal to the differences of frequency between said signals and said control oscillations, selecting one of said produced frequencies and re-amplifying, demodulating and further amplifying it.

75 6. The method of household selective radio reception controlled from a distance which comprises, collecting all available signals in the range of the receiver within a predetermined band of frequencies covering a plurality of signal channels, producing oscillations of a control frequency and radiating the same a short distance, collecting said oscillations, amplifying said oscillations and said signals, detecting said oscillations and said signals so as to produce signals of frequencies equal to the differences of frequency between said signals and said control oscillations, adjusting the frequency of said control oscillations until the desired one of said produced frequencies has a predetermined value, further amplifying said desired frequency and demodulating it.

80 7. A single control household radio receiver comprising pick-up means for receiving radio frequency oscillations, untuned means for amplifying oscillations, a portable control unit remote from said pick-up and amplifying means and including means for producing control oscillations and single 85 means for adjusting the frequency thereof, detector means connected to said untuned amplifying means for producing heterodyne frequencies from the interaction of such control oscillations and received broadcast sig- 90
